HYDRAULIC CONTROL VALVE

John C. Freeborn, Richfield, Minn., assignor to Minneapolis-Honeywell Regulator Company, Minneapolis, Minn., a corporation of Delaware

Filed Mar. 27, 1961, Ser. No. 98,688

6 Claims. (Cl. 121—150)

My invention relates to hydraulic control valves of the time modulated type and more particularly to a hydraulic type multivibrator with simplified electric control.

Time modulated hydraulic control valves are known and used, but they generally have limited application because of the complexity of the structure involved. Valves of this type generally employ either complex electrical control circuitry for vibrating the hydraulic control valve or complex hydraulic switching circuitry to provide the wave generation output from the hydraulic valve. While apparatus of this type is desirable from the standpoint of accurately positioning and controlling loads, the complexity of the structure has generally limited the application of this type of control. The present application is directed to an improved type of hydraulic control valve or hydraulic multivibrator which has a square wave type output for time modulation control on associated devices. This application is an improvement over the copending application of Robert V. Burton, now Patent 2,996,045, dated August 15, 1961, on a Time Modulated Hydraulic Servo Valve. In the Burton application the switching of the main control valve is done through auxiliary switching and timing valves in accordance with the controlled flow through regulated orifices. In the present invention the switching of the main control valve is done through regulation of pressure applied to the motive section of the control valve and an adjustment of the bias on the pressure responsive switching valves associated therewith. Accurate control of the electrical portion of the network is not required and a small amount of current or signal will provide an accurate control over the operation of the hydraulic multivibrator.

It is therefore an object of this invention to provide an improved hydraulic control valve of the time modulated type or a hydraulic multivibrator type control. It is also an object of this invention to provide a valve of this type in which the switching is controlled from the pressure of the hydraulic fluid with small electric signals controlling the shape of the output wave form of the hydraulic multivibrator by adjusting bias on a pressure responsive switching valve. These and other objects of this invention will become apparent from the reading of the attached description together with the drawing wherein:

FIGURE 1 is a schematic view of the improved hydraulic multivibrator, and

FIGURE 2 is a schematic wiring diagram of the electrical portion of the hydraulic multivibrator.

My improved hydraulic multivibrator or time modulated control valve is shown schematically in FIGURE 1 as including a main control valve indicated at 10, this control valve being basically a four-way valve of conventional configuration. Control valve 10 includes a casing 11 and a spool, indicated generally at 12, this spool having four land portions 14, 15, 16 and 17 with dwell portions 18, 19 between the land portions. Casing 11 includes a plurality of conduits connected thereto including a supply pressure conduit indicated at 20, return line conduits indicated at 21 and a pair of cylinder or outlet conduits indicated at 22, 23 respectively. The operation of this control valve is conventional with four-way valve operation, in that movement of the spool 12 will position the lands 15 and 16 relative to the outlet conduits 22, 23 such that one or the other will be connected with supply conduit 20 through the dwell portion 19 while the oppo-

2

site outlet conduit will be connected through the dwell portion 18 outside of the lands 15, 16 to the return conduit 21. The valve spool 12 is moved within the cylinder casing 11 by means of pressure differential applied to the motive means or ram portions of the valve. These motive means or ram portions of the valve are defined as a chamber within the casing 11 located to either side of the external land portions 14, 17 of the valve spool. For purposes of identification these ram portions or motive chambers are identified at 25, 26 respectively.

The outlet conduits 22, 23 of the control valve are connected respectively to the opposite inlet extremities of the device to be actuated 30, shown herein as a simple bidirectional hydraulic actuator. The actuator is comprised of a casing 31 having inlet extremities at 32, 33 at the extremities thereof to which the outlet conduits 22, 23 of the control valve are connected. The actuator also includes a piston 35 slideably positioned within the cylinder and defining motive chambers within the cylinder to which the inlets are attached. Piston 35 has output shafts 38 connected thereto or integral therewith which are guided by end plates or guides 40 integral with ends of the casing 31. The hydraulic output from the control valve 10, which is the main valve of the hydraulic multivibrator, is of the square wave type. That is, its output pressure variations due to control movement of the movable element or spool 12 will cause pressure variations to the device 30 to be actuated to provide an ultimate movement of the piston or output shaft 38 in accordance with the over-all pressure differential applied to the extremities of the casing 31. This movement of the device to be actuated will be time modulated in accordance with the length of time of each half cycle of pressure variation in the output wave form of the hydraulic multivibrator.

The operation of the control valve 12 through the motive sections or ram sections 25, 26 thereof is controlled by a timing valve 50 or variable pressure means also connected to the outlet conduits 23, 22 such as is indicated by the conduits 41, 42 respectively, which include directional check valves 44, 45. The timing valve actually comprises a cylindrical casing 51 having a floating piston 52 therein, the piston being slideably positioned within the casing to define variable pressure chambers such as is indicated at 53, 54 respectively within the casing to either side of the piston 52. Positioned within the pressure chambers 53, 54 are centering springs 55, 56 respectively, these springs bearing against the extremities of the casing 50 and the piston 52 for centering purposes. The inlet conduits 41, 42 connect to the casing 51 and hence the chambers 53, 54 through inlet conduits indicated at 57, 58 respectively. Also connected to the pressure chambers or the inlet conduits 57, 58 are additional conduit means 60, 61, which include orifices 62, 63. The conduit means 60, 61 provide a means by which pressure within the chambers 53, 54 may be bled to a common conduit 65 connected to the return line conduit similar to or the same as conduit 21. The orifices 62, 63 are fixed and control a fixed rate of bleed from the pressure chambers 53, 54 depending upon the pressure therein, and the pressure chambers of the timing valve 50 are basically supplied by pressures in the outlet conduits 22, 23 except during the conditions when the respective conduits 22 or 23 are connected to the return line conduit 21. At such a time the check valves 44 or 45 prevent communication of the chambers 53, 54 with the outlet conduit except as through the restrictions 62, 63 and the common conduit 65.

In addition to the conduits 41, 42 and 60, 61 leading to and from the pressure chambers 53, 54 of the timing valve or pressure responsive means controlling the operation of the control valve 10, additional conduit means or conduits 70, 71 are connected to these pressure chambers

and lead therefrom through directional check valves 72, 73 respectively in the conduits to the ram sections or motive means 26, 25 of the control valve to supply hydraulic fluid thereto for operation of the valve. The directional check valves 72, 73 in these conduits normally prevent reverse flow from the motive means or ram sections back to the pressure chambers 53, 54 of the timing means and permit only the pressure differential from the respective pressure chambers 53, 54 to the respective ram sections to effect movement of the valve spool 12 and hence operate the control valve 10. Thus, it will be seen that through the ram sections 25, 26 and the directional check valves 72, 73, the pressure chambers 54, 53 are directly connected across the control valve for operation of the same, and the pressures in the pressure chambers 53, 54 are imparted to the pressure chambers or ram sections 26, 25 of the control valve. Also included as a part of this conduit or connection between the pressure chambers 53, 54 and the ram sections 26, 25 of the control valve are pressure responsive switching valves 80, 81 respectively. Each pressure responsive switching valve includes a casing 82, 83 housing a piston 84, 85 having an operating shaft 86, 87 associated therewith, the pistons being biased within the respective cylinders 82, 83 by means of springs 88, 89 respectively. In the pressure responsive switching valve 80, the upper extremity of the casing 82 is connected by means of a conduit 90 to the conduit 70 above the directional check valve 72 and communicating directly with the ram section or motive means 26 of control valve 10. Similarly the lower extremity of the piston is connected by means of a conduit 91 to the outlet conduit 70 below the directional check valve. This places the piston 84 within the cylinder 82 directly across or between the ram section or motive means 26 of control valve 10 and the pressure in chamber 53 of the timing valve 50. The pressure responsive switching valve 81 similarly has its piston 85 connected across or between the pressure chamber 54 and the ram section or motive means 25 of control valve 10 through a conduit 94 connected to the motive means or ram section 25 of the control valve 10 above the directional check valve 73 and the lower extremity of the casing 83 or the piston 85 connected through a conduit 95 to the conduit 71 below the directional check valve 73 and common with the pressure chamber 54 of timing valve 50. In addition, each switching valve has its respective conduit 70, 71 connected into the side of the cylinder 82, 83 respectively such that the piston when displaced within the cylinder will operate as a valve to effect a bypass around the directional check valves 72, 73. The casings 82, 83 with pistons 84, 85 therein provide relatively large volumes for the fluid in the lines to flow into causing a decrease in line pressure whenever the respective pistons are moved suddenly from one extremity of the casing to the other. This will set up a switching action in a manner later to be described. The movement of the pistons will act as the valve to bypass the directional check valve and allow a rapid change in pressure in the motive chambers 25 or 26 at the extremities of the control valve 10 under certain conditions to effect a rapid movement of the spool 12 within the control valve or casing 11 to effect switching of the supply conduit 20 between the outlet conduits 22, 23. As will be seen in the diagram, the springs 88, 89 apply a bias to the lower extremity of the piston urging the same within the casing 82, 83. In addition, a pair of electromagnetic biasing elements indicated as electromagnets 100, 101 respectively cooperate with pivoted armatures 102, 103 respectively to cooperate with the shafts 86, 87 of the control valves or pressure responsive switching valves 80, 81 by applying additional bias to the respective switching valves. Each of the electromagnets are controlled respectively by coils indicated at 104, 105, the coils being adapted to be selectively energized with a direct current to provide a given attraction between the

5 electromagnet and the pivoted armatures 102, 103 to apply a given force to the respective output shafts or thrust members 86, 87 of the switching valves in a direction to aid the effects of the springs 88, 89.

10 The schematic wiring diagram in FIGURE 2 shows one way of energizing these coils, this circuit including a transformer 110 having a primary winding 105 adapted to be connected to an alternating current source of power and a secondary winding 106 connected across a full wave rectifier indicated generally at 107. The output diagonals of the full wave rectifier are connected respectively to the extremities of the coils 104, 105 such that an extremity at each of the coils 104, 105 are connected in common to one output diagonal of the rectifier while the opposite output diagonal is connected through an adjustable potentiometer indicated at 109 to the opposite extremities of the coils 104, 105 such that the coils may be selectively and variably energized with a direct current source of power in a differential manner.

15 In operation, this hydraulic multivibrator or time modulated hydraulic servo valve operates on a load or device to be controlled in a conventional manner. I have shown the load 30 herein as a floating piston type actuator 30 which is controlled by valve 10 through the variation in oscillation of the carrier frequency at the output conduits 22, 23. The carrier frequency will control flow to the opposite extremities of the piston 35 within the load device or actuator 30 to vary the rate of movement of the piston in one direction or the other. 20 When the device to be actuated is loaded or connected in a closed servo loop, it will be moved to a position in proportion to the differential between on and off time of the control valve or the relative periods of time in which the spool of the control valve is in one position or the other, connecting the pressure supply conduit 20 to the one or the other of the outlet conduits 22, 23. Thus, the control of the load will be in terms of the pressure differential output existing between the conduits 22, 23 on a time basis. It should be recognized that in hydraulic multivibrators or time modulated hydraulic valves of this type the applied pressure ranges on the system would be between about 700 to 3000 p.s.i. to provide an oscillation from the control valve or servo valve in the range of 200 to 300 c.p.s. The actual length of time that the control valve is in one switching position or the other, that is applying pressure directly to one output conduit while the other is connected to the return line within a given cycle will determine the actual pressure differential existing in the device to be actuated and hence the ultimate position of the same in a conventional time modulation type of operation.

25 Thus, in the present device, supply pressure from inlet supply port 20 is directed through the control valve 10 to one or the other of the outlet conduits 22, 23 depending upon the position of the valve spool 12 or the movable element thereof. Movement of the spool or valve element is controlled by the pressure differential existing between the motive means or ram sections 25, 26 at the extremities of the valve spool. The outlet conduits 22, 23 are connected in addition to the pressure chambers 53, 54 of the timing valve 50. Thus in the position or condition of the apparatus shown in FIGURE 1, the pressure chamber 54 of valve 50 is connected to the supply conduit 20 through the outlet conduit 22 and directional check valve 45 while the pressure in chamber 53 bleeds down from the pressure level which exists therein prior to switching. The directional check valve 45 prevents communication of this chamber with the return line conduit 21 through the conduit 41. Both pressure chambers 30 53, 54 are, however, connected through restrictions 62, 63 to the return line conduit 65 leading to the conduit 21 or the equivalent thereof. Thus, supply pressure will be bled from the chamber 54 through the restriction 63 at the same time that the pressure existing in chamber 53 is bled through the restriction 62 to the return line. This

timing device will control the pressure differential across the ram sections 25, 26 to provide the square wave alternating pressure output from the control valve. The alternating half cycles of pressure are controlled with respect to time as will be later noted through the energization or operation of the electromagnets 100, 101. Thus with the control valve 10 in the position shown the hydraulic fluid existing in pressure chamber 53 is forced through the orifice 62 and the piston 52 is moved from left to right compressing the centering spring 55. The pressure in the chamber 53 will decrease and the piston will slow down as the compression of the spring 55 builds up. The pressure in area 54 of the timing valve 50 is communicated or transmitted through the check valve 73 to the ram section 25 and hence through the control valve by virtue of application to the spool 12 to the top of the piston 84 of pressure responsive switching valve 80 through the conduits 70 and 90. The directional check valve 72 prevents this pressure from being transmitted into the pressure chamber 53. Similarly, the pressure of chamber 53 is transmitted through the conduits 57, 70 and 91 to the bottom of the switching piston 84 of switching valve 80. Thus, the pressure differential existing on the timing valve is also applied to the pressure responsive switching valve 80 causing the piston therein to gradually move against the bias of the spring 88 and the bias of the electromagnet 100. When sufficient pressure differential exists between the areas of the pressure chambers 53, 54 and hence the top and bottom of the piston 84 of the switching valve 80, the magnetic attraction of the electromagnet 100 will be overcome and the armature 102 will be forced down away from the electromagnet through the thrust of the shaft 86 attached to the piston and will rapidly move when the magnetic attraction is broken providing a bypass around the directional check valve 72. The bypass connection allows conduit 90 to communicate directly with the conduit 70 and 57. This action will permit a rapid change in pressure in the chamber 26 or an increase in the pressure differential existing between the ram sections 25, 26 causing the control valve 10 or the movable element or spool 12 thereof to transfer completely to the right extremity of the casing 11. In this position the supply pressure port 20 will be connected to the outlet conduit 23 and the outlet conduit 22 will be connected through the dwell portion 18 to the return line conduit 21. At the same time the device to be actuated or floating piston actuator 39 will have its respective inlet connections reversed with respect to supply and return lines causing the piston to be subjected to a pressure differential in the opposite direction.

Once transfer of the control valve 10 has been completed pressure differential will no longer exist across the piston 83 of switching valve 80 and it will return to its normal position by means of the light spring 88 while the operation or energization of electromagnet 100 will cause its respective armature or flapper 102 to be attracted thereto. The pressure in chamber 54 may still exceed that existing in pressure chamber 53 by virtue of the compressed spring 55 in chamber 53 and the relatively small volume of oil necessary to move the control valve 10. However, the pressure chamber 53 is now at the supply pressure and pressure chamber 54 sees supply pressure plus a light spring force with this chamber being bled to the orifice 63 to the return line and being sealed directly from the return line through the control valve by the check valve 45. Pressure in the chamber 54 diminishes or is reduced by virtue of the leak through the orifice 63 as the timing valve or the piston 55 thereto moves from right to left just as the pressure in chamber 53 previously was diminished. This diminishing pressure applied to the base or lower extremity of piston 85 of the pressure responsive switching valve 81 will cause the pressure differential to increase between top and bottom of the piston communicating with the ram section 26 and the pressure chamber 54 respectively to overcome the biasing force

of electromagnet 101 and to repeat the switching action. Thus, whenever this pressure differential reaches a prescribed value the attractive force of the electromagnet 101 and the spring 87 will be overcome causing the piston 5 to snap down and allowing a bypass around the directional check valve 73 to unload the ram section 25. This will effect a transfer of the control valve or the spool 12 thereof from right to left reconnecting or reversing the connections between the supply pressure conduit 20 and the outlet pressure conduit 22. Hence the pressure differential to the device to be actuated 30 will be reversed with the next half cycle of output frequency.

The relative strength of the solenoids or electromagnets 100, 101 as controlled by the current flow through the respective coils 104, 105 thereof will be converted into a time modulated hydraulic control adjusting the length of time which the control valve will remain in one switching position or the other and hence the length of each half cycle of frequency of output wave form. This wave form will determine the ultimate pressure differential to be applied through the outlet conduits 22, 23 to the device to be actuated. FIGURE 2 shows merely one means for deriving a direct current of varying amplitude to the respective coils 104, 105 from an alternating current source, it being understood that the potentiometer may be adjusted to either side of a normal or central position to selectively vary the magnitude of current flow differentially through the respective coils to adjust the on or off time and hence the output wave form of the carrier frequency from this control valve. This time modulated control can be effective without the need for precision hydraulic parts as presently required in devices of this type.

In considering this invention it should be remembered that the present disclosure is intended to be illustrative only and the scope of the invention should be determined only by the appended claims.

I claim as my invention:

1. A hydraulic multivibrator comprising: a control valve having a movable element and including a supply pressure conduit, a return line conduit, and a pair of outlet conduits; said outlet conduits being adapted to be connected to a device to be actuated by said hydraulic multivibrator; motive means included at the extremities of the movable element for said control valve and adapted to selectively control the position of the same relative to said conduits to effect switching of a said supply pressure conduit to one of said outlet conduits and said other of said outlet conduits to said return line conduit; pressure actuated timing means including a cylinder having a floating piston therein defining pressure chambers at either extremity of said cylinder and including centering springs in said pressure chambers acting on said piston; conduit means connecting said pressure chambers of said timing means to said outlet conduits; directional check valve means included in said last named conduit means; additional passage means including restrictions connecting the pressure chambers of said timing means to said return line conduit; additional conduit means connecting the pressure chambers of said timing means and motive means of said control valve such that the pressure differential existing in the pressure chambers of said timing means will cause operation of said control valve; directional check valve means included in said additional conduit means and preventing flow reversal from said motive means of said control valve to the pressure chambers of said timing means and the restricted passages connected thereto; pressure responsive valve means connected to and normally communicating with the motive means of said control valve and the pressure chamber of said timing means in a bypass connection around said last named directional check valve means, said pressure responsive valve means being operative upon a predetermined pressure differential to bypass said directional check valve means allowing rapid change in pressure in one or the other of said motive means of said control

valve to cause the movable element of said control valve to rapidly move between operating positions and effect switching of said supply pressure conduit to the opposite outlet conduit thereof; and electromagnetic biasing means for each of said pressure responsive valve means including a coil adapted to be selectively energized to determine the pressure differential controlling the operation of said pressure responsive valve means and the operation of said control valve.

2. A hydraulic multivibrator comprising: a control valve having a movable element and including a supply pressure conduit; a return line conduit, and a pair of outlet conduits; said outlet conduits being adapted to be connected to a device to be actuated by said hydraulic multivibrator; motive means included at the extremities of the movable element for said control valve and adapted to selectively control the position of the same relative to said conduits to effect switching of a said supply pressure conduit to one of said outlet conduits and said other of said outlet conduits to said return line conduit; pressure actuated timing means including means defining variable pressure chambers; conduit means connecting said pressure chambers of said timing means to said outlet conduits; directional check valve means included in said last named conduit means; additional passage means including restrictions connecting the pressure chambers of said timing means to said return line conduit; additional conduit means connecting the pressure chambers of said timing means and motive means of said control valve such that the pressure differential existing in the pressure chambers of said timing means will cause operation of said control valve; directional check valve means included in said additional conduit means and preventing flow reversal from said motive means of said control valve to the pressure chambers of said timing means and the restricted passages connected thereto; pressure responsive valve mean connected to and normally communicating with the motive means of said control valve and the pressure chamber of said timing means in a bypass connection around said last named directional check valve means, said pressure responsive valve means being operative upon a predetermined pressure differential to bypass said directional check valve means allowing rapid change in pressure in said pressure chambers of said timing means and one or the other of said motive means of said control valve to cause the movable element of said control valve to rapidly move between operating positions and effect switching of said supply pressure conduit to the opposite outlet conduit thereof; and electromagnetic biasing means for each of said pressure responsive valve means including a coil adapted to be selectively energized to determine the pressure differential controlling the operation of said pressure responsive valve means and the operation of said control valve.

3. A hydraulic multivibrator comprising: a four way control valve having a supply pressure conduit, a return line conduit, and a pair of outlet conduits connected thereto; said outlet conduits being adapted to be connected to a device to be actuated by said hydraulic multivibrator; motive means included with said control valve and adapted to selectively control the operation of said valve to effect switching of said supply pressure and said return line conduits between said outlet conduits; pressure actuated timing means including a cylinder having a floating piston therein defining pressure chambers at either extremity of said cylinder; conduit means connecting said pressure chambers of said timing means to said outlet conduits; directional check valve means included in said last named conduit means; additional passage means including restrictions connecting the pressure chambers of said timing means to said return line conduit; additional conduit means connecting the pressure chambers of said timing means and motive means of said control valve such that the pressure differential existing in the pressure chambers of said timing means will cause operation of said control

valve; directional check valve means included in said additional conduit means and preventing flow reversal from said motive means of said control valve to the pressure chambers of said timing means and restricted passages connected thereto; pressure responsive valve means connected to and normally communicating with the motive means of said control valve and the pressure chamber of said timing means in a bypass connection around said last named directional check valve means, said pressure responsive valve means being operative upon a predetermined pressure differential to bypass said directional check valve means allowing rapid change in pressure in one or the other of said motive means of said control valve to cause rapid operation thereof to switch said supply pressure conduit to the opposite outlet conduit thereof; and electromagnetic biasing means for each of said pressure responsive valve means including a coil adapted to be selectively energized to determine the pressure differential controlling the operation of said pressure responsive valve means and the operation of said control valve.

4. A hydraulic multivibrator comprising: a four way control valve having a supply pressure conduit, a return line conduit, and a pair of outlet conduits connected thereto; said outlet conduits being adapted to be connected to a device to be actuated by said hydraulic multivibrator; motive means included with said control valve and adapted to selectively control the operation of said valve to effect switching of a said supply pressure and said return line conduits between said outlet conduits; pressure actuated timing means including means defining variable pressure chambers; conduit means connecting said pressure chambers of said timing means to said outlet conduits; directional check valve means included in said last named conduit means; additional passage means including restrictions connecting the pressure chambers of said timing means to said return line conduit; additional conduit means connecting the pressure chambers of said timing means and motive means of said control valve such that the pressure differential existing in the pressure chambers of said timing means will cause operation of said control valve; directional check valve means included in said additional conduit means and preventing flow reversal from said motive means of said control valve to the pressure chambers of said timing means and the restricted passages connected thereto; pressure responsive valve means connected to and normally communicating with the motive means of said control valve and the pressure chamber of said timing means in a bypass connection around said last named directional check valve means, said pressure responsive valve means being operative upon a predetermined pressure differential to bypass said directional check valve means allowing rapid change in pressure in said pressure chambers of said timing means and one or the other of said motive means of said control valve to cause rapid operation thereof to effect rapid switching of said supply pressure conduit to the opposite outlet conduit thereof; and electromagnetic biasing means for each of said pressure responsive valve means including a coil adapted to be selectively energized to determine the pressure differential controlling the operation of said pressure responsive valve means and the operation of said control valve.

5. A hydraulic multivibrator comprising: a control valve including a supply pressure conduit, a return line conduit, and a pair of outlet conduits; said outlet conduits being adapted to be connected to a device to be actuated by said hydraulic multivibrator; motive means included in said control valve and adapted to selectively control the operating condition of the valve relative to said conduits to effect switching of a said supply pressure and said return line conduits between said outlet conduits; pressure actuated means having a pair of variable pressure chambers connected to said outlet conduits and though restrictions to said return line conduit; additional

conduit means connecting said pressure chambers to motive means for said control valve such that the pressure differential existing in the pressure chambers will cause operation of said control valve; directional check valve means included in said additional conduit means to prevent flow reversal from said motive means of said control valve to said pressure chambers; pressure responsive valve means connected to and normally communicating with the motive means of said control valve and said pressure chambers in a bypass connection around said directional check valve means, said pressure responsive valve means being operative upon a predetermined pressure differential to bypass said directional check valve means allowing rapid change in pressure in one or the other of said motive means of said control valve to cause rapid operation of said valve and switching of said supply pressure conduit between opposite outlet conduits; and electromagnetic means for said pressure responsive valve means operative when variably energized to vary the pressure differential at which said pressure responsive valve means responds to control the operation of said control valve.

6. A hydraulic multivibrator comprising: a control valve having a movable valve spool and including a supply pressure conduit, a return line conduit, and a pair of outlet conduits; said outlet conduits being adapted to be connected to a device to be actuated; a ram section included at each of the extremities of the movable spool of said control valve and adapted to selectively control the position of the same relative to said conduits to effect switching of a said supply pressure conduit to one of said outlet conduits and said other of said outlet conduits to said return line conduit; pressure actuated timing means including a cylinder having a floating piston therein defining variable pressure chambers between either extremity of said cylinder and said piston; conduit means connecting said pressure chambers of said timing

means to said outlet conduits to provide varying pressures thereto; directional check valve means included in said last named conduit means; additional passage means including orifice means connecting the pressure chambers of said timing means to said return line conduit to bleed pressure from said pressure chambers; further conduit means connecting respectively the pressure chambers of said timing means and ram sections of said control valve such that the pressure differential existing in the pressure chambers of said timing means will cause operation of said control valve; directional check valve means included in each of said further conduit means preventing flow reversal from said ram sections of said control valve to the pressure chambers of said timing means; pressure responsive valve means connected to and normally communicating with the ram sections of said control valve and the pressure chambers of said timing means in a bypass connection around said last named directional check valve means, said pressure responsive valve means being operative upon a predetermined pressure differential to bypass said directional check valve means allowing rapid change in pressure in one or the other of said ram sections of said control valve to cause the movable valve spool to rapidly move between operating positions and effect switching of said supply pressure conduit between the outlet pressure conduits; and electromagnetic biasing means for each of said pressure responsive valve means including a coil adapted to be selectively energized to determine the pressure differential necessary to operate said pressure responsive valve means to control operation of said control valve.
